UNITED STATES PATENT OFFICE.

LEWIS J. IVES, OF MEDINA, NEW YORK, ASSIGNOR, BY MESNE ASSIGNMENTS, TO CHARLES F. BEEBE, OF DETROIT, MICHIGAN.

WIRE FENCE.

SPECIFICATION forming part of Letters Patent No. 537,117, dated April 9, 1895.

Application filed July 24, 1893. Serial No. 481,270. (No model.)

To all whom it may concern:

Be it known that I, LEWIS J. IVES, a citizen of the United States, residing at Medina, in the county of Orleans and State of New York, have invented certain new and useful Improvements in Wire Fences; and I do hereby declare the following to be a full, clear, and exact description of the invention, such as will enable others skilled in the art to which it applies to make and use the same, reference being had to the accompanying drawings, and to figures of reference marked thereon, which form a part of this specification.

My invention relates to that class of fences which consist of a number of parallel wires tightly stretched between posts. A uniform tension of these wires is requisite and various devices are employed for tightening them and automatically regulating any variations in tension due to the longitudinal expansion or contraction of the wires.

With this end in view my invention consists of improved means for accomplishing this purpose.

I will now proceed to describe minutely the manner in which I have carried out my invention and then claim what I believe to be novel.

In the drawings, Figure 1 is an elevation of my improved fence. Fig. 2 is an enlarged view of a part of the same; and Figs. 3 and 4 are detached side and front elevations of the combined wire tightener and tension equalizer.

Referring to the drawings, 1 and 2 are the end posts between which the parallel wires 3 are stretched to form the fence. Each post has two pieces of plank 4. 4. placed edgewise on opposite sides and firmly attached to the post at or near the lower end. The ends of these pieces 4. 4. project sufficiently to receive two other pieces of plank 5. 5. which are laid flat upon the pieces 4. 4. and secured to the same after the dirt has been thoroughly packed to the top edges of the pieces 4. 4. and over these united pieces the dirt is tightly packed to the surfaces thus preventing the post from heaving or drawing out under strain.

An anchor-post 6 is set in line with the fence about eight or ten feet from the end

post 1 and the braces 7. 7. are framed into the upper ends of the end and anchor posts in an inclined position as shown. The anchor-post 6 is tied to the end post 1 by the wire 8. This 55 prevents the end and anchor posts from spreading apart under the heavy strain exerted by the intermediate braces 7. 7. caused by the stretching of the wires 3 between the end posts 1 and 2 of the section. Between and 60 in line with the end posts 1 and 2 are set at requisite distances intermediate posts into which are driven the staples 10 for the loose reception of the wires 3 passing through them. These wires are fastened to the post 1 in any 65 suitable manner, their other ends passing through the end post 2 and secured to and operated by the combined tightener and tension equalizer which I will now describe in detail.

11 is a stiff bow-spring made of sheet steel the inner side of which rests when in position against the post 2 its outer side at its upper free end carrying the plate 12 riveted thereto and provided with open bearings 13. 70 13. adapted for the reception of the winding-shaft 14 having the circular grooves 15. 15. in which the open bearings 13 ride. One end of the wire 3 to be stretched is passed through an aperture 16 in the winding shaft 14 and a 75 key or wrench applied to its square end 17 serves to wind the end of the wire around the shaft and tighten it to the required tension. The other end 18 of this shaft 14 is made hexagonal for the loose reception of an hexagonal 80 nut 19 which fits snugly between the end 18 and the plate 12 and serves to lock the shaft and hold the wire 3 in its stretched condition. Before the wire is stretched the normal position of the spring 11 is shown in dotted lines 85 in Fig. 3. A spiral spring 20 surrounds the wire 3 and rests when in operative position between the ends of the spring. An elongated orifice 21 in the plate 12 and attached spring permits of free play of the wire 3 as it is being tightened. When the wire is sufficiently tightened, the spring 11 is compressed as shown in full lines in Fig. 3 and in this position is susceptible of sufficient play in either direction to compensate for any expansion or 90 contraction of the wire so held thus forming an automatic tension-equalizer. The coiled

spring 20 interposed between the ends of the flat spring 11 serves to assist this spring in its equalizing action and forms at the same time a compressible bumper to prevent accidental breaking of the spring. A rubber or other form of spring might be substituted in place of the coiled-spring herein shown. At suitable distances apart are placed the perpendicular stay wires 21 provided with loops 22 preferably in alternate side through which the wires 3 can pass easily, and fastened to the top and bottom wires by means of smaller wire 23, that can be easily twisted through the upper and lower loops in the stay-wire 15 and wound around the upper and lower wires in each direction to prevent slipping. In constructing this stay it is important that the loops be made large enough to permit the wires 3 to pass through easily, as in building 20 the fence the stay-wires are fastened to the upper and lower wires as described and the intermediate wires are then threaded through these loops. This stay differs from similar ones used in other fences in that it is not 25 twisted on the horizontal wires but is so arranged that these wires pass freely through it. In using this form of stay I am enabled, to employ heavier wire and machine made, thus obtaining more durability and greatly 30 strengthening and stiffening the fence. In addition the horizontal wires can be tightened and should any of them break can be quickly repaired by loosening the wire, splicing in a piece and tightening as at first, whereas in 35 fences where the stay is wound around or fastened to such wire repairs cannot be made without taking the fence apart.

By my improved construction just outlined,

the fence can at any time be taken down and removed to other localities, if desired, without injury to the other parts, by simply loosening the wires and drawing them out of the stay-wires and then untwisting the small wires which hold the stay at top and bottom and removing the top and bottom wires. 45

One serious objection offered to wire fences is that animals do not at times see them and are often injured by accidentally colliding with them. To obviate this I provide the narrow strip of board 24 which I secure to and 50 in line with the top wire by staples 25 and to the stay-wires by staples 26 thus securely holding it in position.

I claim—

1. In a wire fence the combination with a 55 post, of a wire passing through the said post, a bow-spring having its inner end bearing against the outer side of the post and a tightener upon the outer end of the bow-spring, to which the wire is secured substantially as 60 shown and described.

2. In a wire fence the combination with a post, of a wire passing through the said post a bow-spring having its inner end bearing against the outer side of the post, a tightener 65 upon the outer end of the bow-spring to which the wire is secured and a compressible bumper interposed between the ends of the bow-spring substantially as shown and described.

In testimony whereof I have signed my 70 name to this specification in the presence of two subscribing witnesses.

LEWIS J. IVES.
